JOSEPH PERCY REMINGTON, OF PHILADELPHIA, PENNSYLVANIA.

POSITIONING AND FEEDING MECHANISM FOR CONFECTION-WRAPPING MACHINES.

Application filed May 3, 1917. Serial No. 166,184.

To all whom it may concern:

Be it known that I, JOSEPH PERCY REMINGTON, of Philadelphia, in the county of Philadelphia and State of Pennsylvania, have invented certain new and useful Improvements in Positioning and Feeding Mechanism for Confection-Wrapping Machines, whereof the following is a specification, reference being had to the accompanying drawings.

The invention relates to mechanism whereby confections of a generally conical form are properly set up, aligned, and fed to a wrapping mechanism to be individually wrapped in tin foil or similar envelopment. While my invention is especially adapted to handling such chocolate confections, it is to be understood that the invention is not thus limited, but covers the similar setting up, aligning and feeding of similar articles.

In the accompanying drawings, Fig. I, is a plan view of a wrapping machine conveniently illustrating the adaptation of my invention thereto.

Fig. II, is a side elevation of the same.

Fig. III, shows a partial plan view of the left hand end of the machine.

Fig. IV, is a similar view of the right hand end of the machine.

Fig. V, is a longitudinal sectional view through the portion of the machine shown in Fig. III, taken on the line V—V in Fig. III.

Fig. VI, is a detail of the mechanism for intermittently operating the main feed carrier.

Fig. VII, illustrates a sectional view through the discharge end of the supply hopper and the means for regulating the flow of the articles to be wrapped.

Fig. VIII, is a longitudinal sectional view through the portion of the machine comprehended in Fig. IV, as designated on the said figure by the arrows VIII—VIII.

Fig. IX, is a partial plan section along the line IX—IX in Fig. VIII.

Fig. X, is a detail plan on an enlarged scale showing the terminal ends of the runways and the tolling mechanism therefor.

Fig. XI, represents a section along the line XI—XI in Fig. X.

Figs. XII, and XIII, are detail perspective views of the slip feeds.

Fig. XIV, is a similar view of one of the tilting devices associated with the runways.

Figs. XV, XVI, XVII, and XVIII, are detail views of one of the runways illustrating the method of guidance and also the ejection of improperly placed confections.

Figs. XIX and XX, illustrate the operation of the tilting device shown in detail in XIV.

In the drawings, the hopper 1, which is kept full of confections, is provided at its bottom with an inclined chute 2, leading to an outlet slot protected by a gate 3, which may be suitably adjusted to vary the height of the outlet slot, and consequently the rate at which confections will be fed by gravity from the hopper. Directly beneath this outlet slot, is an endless traveling carrier 4, running on rollers 5, and 6, of which the latter is driven by the worm gear 7, (see Fig. V), actuated by the belt 8, driven by a pulley geared to the main shaft 9, which is driven by a worm gear from a shaft 25, which is in turn actuated from the motor shaft 10. Supplemental vertical endless bands 11, 11, protect the edges of the carrier 4, and travel with it, being driven by the bevel gears 12, (see Fig. III).

By the operation of the parts thus described, a continuous supply of confections passes from the hopper on to the endless carrier, and is by it discharged promiscuously upon the inclined chute 13. This chute has small perforations 14, formed in it, which permit any crumbs or foreign substances which may be fed from the hopper, to be discharged at this point by way of the chute 15, (Fig. V).

Beneath the discharge end of the inclined chute 13, is the basing or setting up table 16, over the surface of which runs the endless carrier 17. The peculiarity of the motion of this table is that while the whole table reciprocates longitudinally in relation to the machine, the receiving end of it is given a coincident lateral motion. At the same time the endless carrier 17, is given intermittent forward motion. The carrier 17, passes around rollers 18, and 19, which rest in bearings carried by the frame of the table. Of this frame, one cross-piece 20, nearest the receiving end, is pivoted upon a crank 21, set upon vertical shaft 22, driven by the bevel gear 23, from a shaft 24, actuated by a belt from the countershaft 25, by which the main shaft is driven. The other cross-piece 26, of the frame of the table, is

pivoted upon a block 27, which slides longitudinally in guides 28.

The drive for the endless carrier 17, is an intermittent one, occasioned by the pawling mechanism shown in Fig. VI, the arm of which is connected by a link 29, to the fixed pivotal support 30, as the result of which the endless carrier which covers the surface of the setting up table has a compound motion, consisting of a longitudinal reciprocation along with the whole table, a lateral reciprocation at the receiving end only of the table, and an intermittent drive operating only as the table moves forward. This combination of motions effects a peculiar joggling of the confections, which have been fed upon it, of such intensity as to tumble them about, the joggling motion being strong enough to constantly right or set upon the flat end, confections resting upon their side, although not strong enough to overturn confections which have been righted. One of the reasons why this action takes place is that an article of generally conical form when resting on its conical surface adds the momentum of its rotary motion to the motion of the joggling surface upon which it rests, while when resting on its base no such momentum exists. As a result of the travel of the confections from one end to the other of this setting up table, nearly all of the confections before reaching the discharge end have been righted or set upright.

Touching the upper surface of the carrier 17, is a brush 33, which derives its rotation from the motion of the carrier. It is useful to spread or distribute the confection more evenly across the width of the carrier 17, and to limit any momentarily too rapid feeding of the confections down the chute 18.

To further assist the joggling motion of the surface of the setting up table, in setting up the confections, a series of guiding surfaces 34, are mounted just above the surface of the carrier in fixed relation to the framework of the machine, and in positions inclined to the long axis of the table, whereby the joggling motion of the carrier constantly drives the confections which rest upon it against these guiding surfaces which thus assist in righting the confections and also arrange them in lanes running lengthwise of the table. Subsequent edge guides 35, push confections toward the entrance of the runways, which will shortly be described.

The endless carrier 17, is maintained properly taut by the tension roller 36, mounted on the bell crank lever 37, and capable of being adjusted by the turn buckle 38, as clearly seen in Fig. V.

Should the mechanisms which have been described, be feeding confections more rapidly than the runways can receive them,

or should one or more runways become clogged, any surplus confections rejected by the filled runways pass toward the sides of the table and are discharged by the carrier upon the chute 39, whence such overplus can be collected in a receptacle 40, (Fig. II), and returned to the hopper from time to time.

From this point the confections are distributed among a series of parallel runways each leading to its own wrapping mechanism. In the machine illustrated in the drawings, four such runways are shown, but it will be understood that the number may vary as may be found convenient.

The carrier 17, discharges by way of an inclined chute 41. Along this chute and overhanging the discharge end of the carrier are the guide strips 42, spaced to form entrances to the runways and partitions between them. Below the discharge end of the chute 41, is another series of guiding walls 43, which accomplish a narrowing of the runways. Corresponding to each of these runways and forming a travelling bottom therefor is an endless carrier band 44, mounted at one end upon a pulley on the shaft 45, and at the other end by a similar pulley on a shaft 46. The shaft 45, is supported upon levers 47, counter-weighted by the weight 48, whereby a similar and adjustable tension is put upon all of the endless bands. The shaft 46, is driven by a geared connection with the shaft 91, (see Fig. II), which is involved in a sprocket-drive from the shaft 92.

The endless bands pass between the guiding walls 43, and then across an opening 49, where the runways and the bands lack any side protection, and the bands are subjected to tilting means. Extending across this opening immediately beneath the bands is a rock shaft 50, to the operative crank of which is pivoted a link 51, driven by a crank on the end of the shaft 46. This rock shaft 50, carries tilting collars 52, set one beneath each band. One of these is clearly shown in perspective in Fig. XIV. It is provided with two inclined surfaces, one sloping in one direction, and the other in the other, and so related to each other that as the shaft rocks, these inclined surfaces successively push against the lower side of each endless band, and tilt it first to one side and then to the other. The inclination of these surfaces as shown in Figs. XIX and XX, is not sufficient to cause confections resting upright thereon, to tumble off the band, but if confections have reached the band resting upon their side, as shown in Fig. XX, the inclination or tilting of the band, due to the tilting collar causes it to fall off, dropping down to a receptacle 40, whence confections thus eliminated may be

returned from time to time to the hopper. The open sections of the channels also provide a means of eliminating an excess of confections, since such excess cannot remain 5 on the belts where there are no sides to the channels.

For the remainder of its operative travel, each endless band passes along a metal channel 53. Initially, this channel has low edges, 10 as shown in Fig. XVI, but first one and then the other edge is turned partway over, as illustrated in Figs. XVII and XVIII, so that during the latter part of its travel, the band draws the confections through a partially closed channeled runway of such 15 shape that the confections are confined in their lateral movement, so that they cannot stagger enough to lock, and in their vertical movement so that they cannot capsize. The edges of the channel 53 at the beginning of 20 their inturned portions are inclined as shown in Fig. XV, so that any confections which by any possibility pass the setting up table 16 and the tilting mechanism illustrated in 25 Figs. XIX and XX on their sides, as shown in Fig. XV, are naturally rejected and thrown sidewise from the channel. This tends especially to eliminate misshapen or abnormal shaped confections, since confections of perfectly normal shapes will not 30 usually pass the tilting mechanism unless resting on their bases.

In dropped goods, notwithstanding the variations in shape to which they are subject, 35 there is naturally a plane at a determinable height above the base at which all the goods have a common cross-section, and the channel 53, is so shaped that the line of contact of the channel sides, touches the sides 40 of the confections in this plane. Below this plane, on the other hand, the shape and dimensions of the channel 53 enable it to accommodate any upright confections whose forms are not so far beyond the normal 45 range of variation as must prevent their reaching this portion of the channel.

As the confections pass along the runways, they are subject to inspection and the rejection 50 of any imperfect or mis-shaped confections may be thus manually facilitated if desired.

A clutch on the shaft 25, is operated by the lever 62, (see Fig. I), the end of which is connected by a pin and slot connection 55 with the transverse shifting rod 63, by the movement of which the entire machine can be quickly started or stopped by the operator from a point where the lines of traveling confections are subject to inspection.

The channels 53, lead each to a point 60 which is in juxtaposition to the plungers by which the wrapping operation is effected, as will be hereafter described. The end of each channel is protected by a gate 55, forming 65 part of the slip feed 56, by which, when the

gate is opened, the endmost confection is received and tolled off to one side, and deposited upon the envelopment table, in proper position. The motion of these slip feeds and the gates which they carry, is a transverse motion, which is accomplished by reciprocation of a slide bar 57, carrying spring clips 54, to which the slip feeds are attached. This slide bar 57, (see Fig. XI), is pivotally attached at one end to a pivoted lever 58, spring pressed against a cam 59, by the rotation of which the slide bar is reciprocated to effect the intermittent opening of the terminal gate of each channel, and the feeding of the endmost confection to the envelopment table for wrapping, as hereinafter described.

The spring clips are slidably set upon the slide bar 57, subject to the adjustable pressure of flat springs interposed between the side of the spring clip and the opposing side of the slide bar, (see Figs. X to XIII). This permits the slip feed to remain stationary, notwithstanding the reciprocation of the slide bar, in the contingency that a confection is but partially fed from the runway channel as shown in Fig. X. Fixed stops 60, and 61, put a proper limit to the play of the spring clips upon the slide-bar.

The wrapping mechanism herein shown forms the subject matter of an application filed by me under date of December 4, 1915, Serial No. 65006, and will, therefore, not be described in detail. A general explanation of the same will, however, facilitate the understanding of the prefered type of wrapping mechanism with which the present invention may be successfully associated.

The wrapping mechanism is substantially confined within a superstructure 70, comprised by the side frames of the machine (see Figs. I, II, IV, VIII and IX). The tin foil is drawn from a supply roll 71, and through the instrumentality of a guide roll 72, directed to a pair of co-operative cutting rolls 73, and 74, whereby the web is divided into a plurality of ribbons corresponding in number to that of the channels 53. These ribbons are thereafter passed between the feed rolls 75, and 76, whereby they are horizontally cut into squares of the required size for wrapping the individual confections.

If preferred, the web may be supplied with paper "stickers" which ultimately serve as a lining for the tin foil wrapper. These are provided by a mechanism comprehensively indicated at 77, after the under face of the foil has been supplied with "daubs" of adhesive by the mechanism 78, for this purpose.

After severance by the rollers 75, and 76, the squares cut from the foil are directed by means of belts 79, to a pair of nip rolls 80, and 81, which serve to feed the squares upon the envelopment table 82. As shown in Figs.

IX and X, this table is pierced by a plurality of lobed apertures 83, partially closed by yielding spring pressed hinged plates 85, which normally occupy the position shown.

5 The tin foil squares are advanced, through the action of the nip rolls, into position directly over these apertures and the confections thereafter properly delivered and centered upon these squares by means of the slip 10 feeds of the feeding mechanism already described. A series of plungers 86, respectively aligned with the lobed apertures of the envelopment table, subsequently force the confections together with the foil through the 15 said apertures, while the spring pressed plates yield contemporaneously and in the further progress of the confections, serve to facilitate the envelopment of the same.

20 The confections are deposited by means of the plungers, upon a twisting table 87, which comprises a series of paired bars 88, and 89, whereby the wrappers are finally twisted about the confections and delivered to the discharge chute 90.

25 The several devices above described are all geared or otherwise co-ordinated with the horizontal shaft 9, so as to be operative in proper timed relation with each other, and also with the feeding and aligning mechanism.

30 Having thus described my invention, I claim:

1. In a machine of the class described, means for setting upright promiscuously-fed generally conical objects, which comprise a moving surface upon which the objects are fed, and means for imparting to said surface a joggling motion of such intensity as to be capable of setting up on its 35 base a conical object lying on its side, but not of sufficient intensity to overturn such a conical object standing on its base.

2. In a machine of the class described, means for setting upright promiscuously-fed generally conical objects, which comprise a moving surface, and a fixed guiding surface in juxtaposition to the moving surface, and means for imparting intermittent motion to the moving surface, whereby 40 objects resting upon it are thrown against the fixed surface, the intensity of the motion of the moving surface being such that said objects if resting on their conical surface are thrown against the fixed surface with sufficient force to set them upon their base, but not with sufficient force to effect an overturning of such objects if standing upon their base.

3. In a machine of the class described, a 45 setting up table with an endless carrier passing longitudinally over its face, means for effecting lateral reciprocation of a part of said table, and guiding surfaces held in fixed relation above the moving surface of said table, and so close thereto that objects

resting upon the surface of the table are carried into contact therewith by the motion thereof.

4. In a machine of the class described, feeding and setting up means comprising a table, the surface of which is given a jolting motion, whereby conical objects if resting on their periphery are set up on their base, in combination with means whereby promiscuously-fed conical objects are carried over the surface of said table.

5. In a machine of the class described, feeding and setting up means comprising a table pivotally supported at one end upon a rotating crank and at the other end upon a sliding pivot, with means for effecting the continuous travel of objects from one end of the table to the other.

6. In a machine of the class described, a setting up table, provided with means for setting conical objects on their base, means for effecting the travel of such objects across the surface of the table, during the setting up operation, means for continuously feeding promiscuously-fed objects to the receiving end of the table, and means whereby said objects having been set up during their travel across the table, are fed to one of several similar runways.

7. In a machine of the class described, a setting up table to which confections are fed promiscuously and there set up, a plurality of parallel runways leading each to its own wrapping mechanism, and means for feeding confections from the setting up table to the entrance of each runway.

8. In a machine of the class described, a setting up table to which confections are fed promiscuously and there set up, a plurality of parallel runways leading each to its own wrapping mechanism, means for distributing confections from the setting up table among the runways, and means whereby the setting up table disposes of any surplus confections after the runways are filled.

9. In a machine of the class described, a runway for dropped confections of variable form but all having a plane of common dimension at the same height comprising a channel with overhanging sides affording ample space for accommodating normal variations of form in the portions of the confections below their natural plane of common dimension, but at said plane confining the confections so narrowly as to prevent locking or capsizing.

10. The method of handling or feeding dropped confections of variable form but all having a plane of common dimension at the same height which consists in propelling them on their natural bases while closely confined and guided at their natural plane of common dimension only.

11. In a machine of the class described, a runway, means for feeding a single line of

confections along the runway, and means for tolling off the end confection as it emerges from the runway, consisting of a slide bar reciprocating across the end of the runway, a slip feed held thereon subject to spring pressure, and a gate for the runway forming part of the slip feed.

12. In a machine of the class described, a runway, means for feeding confections along the runway, and means for tolling off the end confection, comprising a slide bar reciprocating across the end of the runway, a slip feed carried thereby and moving across the exit of the runway, and a gate attached to the slip feed whereby after one confection has been tolled off the runway is closed until the return of the slip feed opens it.

13. In a machine of the class described, a runway, means for feeding a single line of confections along the runway, and means for feeding confections, one at a time, laterally from the end of the runway comprising a confection engaging means operating transversely to the end of the runway, a positive operating means therefore and a slip connection between the confection engaging means and the operating means to permit the confection engaging means to remain stationary in the event that a confection is but partially fed from the runway, and a gate for the runway cooperating with said feed.

14. The combination of a setting-up table for setting dropped confections on their bases, and runways receiving confections from said table having channel portions whereby upright confections are confined and guided to wrapping means in such wise that they cannot lock or capsize.

15. The combination of a setting-up table whereon dropped confections are set upon their bases, with means for causing the confections to travel to one end thereof; runways receiving confections from said table having travelling bottoms for conveying the confections and also having guide channel portions whereby upright confections are confined and guided only at their plane of common dimension, in suchwise as to prevent locking or capsizing thereof; and means at the ends of the channels for tolling off upright confections laterally therefrom, one at a time, to corresponding wrapping means.

In testimony whereof, I have hereunto signed my name at Philadelphia, Pennsylvania, this 26th day of April 1917.

JOSEPH PERCY REMINGTON.
